UNITED STATES PATENT OFFICE.

AUGUST J. KEMPIEN, OF ST. PAUL, MINNESOTA.

ELECTRIC LOCK LAMP-SOCKET.

1,032,362.

Specification of Letters Patent.

Patented July 9, 1912.

Application filed October 3, 1908, Serial No. 456,020. Renewed August 12, 1911. Serial No. 643,782.

To all whom it may concern:

Be it known that I, AUGUST J. KEMPIEN, a citizen of the United States, residing at St. Paul, in the county of Ramsey and State 5 of Minnesota, have invented a new and useful Improvement in Electric Lock Lamp-Sockets, of which the following is a specification.

My invention relates to improvements in 10 electric light sockets and has to do more particularly with that class which is provided with means for preventing the removal of the lamp from the socket without the use of a key.

15 The mechanism disclosed in this application is an improvement upon the mechanism disclosed in my Patent No. 738,917 granted on September 15, 1903.

In the accompanying drawings forming 20 part of this specification, Figure 1 is a side elevation of my invention showing the lamp in the socket; Fig. 2 is another side elevation a portion of the lamp being broken away and a portion of the socket removed 25 to expose the interior construction to view, the key being shown inserted so that the lamp can be removed; Fig. 3 is a vertical sectional view in elevation of the threaded inner shell and a block on which said shell 30 is swiveled the capsule or covering being removed and the key shown inserted to allow the lamp to be unscrewed from the inner shell; Fig. 4 is a plan view looking down upon the inner shell, the pintle being shown 35 in section taken upon the line Y—Y of Fig. 3, and Fig. 5 is a perspective view of the key.

In the drawings A represents a lamp having the usual threaded electrical contact 40 thimble B upon its neck B' and C the socket having the capsule or outer shell E of usual construction. The capsule is provided with a head D which is secured thereto by means of a separable connection such as the lock 45 groove and slot 2 and 3. Said shell is also provided with an inner lining 4 of insulating material to prevent current from passing to the capsule from the electrical conducting parts of the socket. In the socket and secured between the head D and a shoulder 50 5 which is formed on the shell is a block or support F made of porcelain or other suitable insulating material and upon which are mounted the contact pieces ultimately connecting with the lamp. Upon one of these contact pieces 6, which is secured to the block

by the screws 7, is a swivel pin or pintle 8 and free to turn upon said pintle is the threaded inner shell 9 of usual form. In the upper end of the inner shell is an insulating disk 10 and between the swivel shell and the contact piece 6 is an insulating washer 11. The lower end of pintle has a head and the upper end is adapted to be upset over the washer 12 to secure the pintle, 60 insulating disk 10, threaded inner shell, insulating washer 11, metal washer 12 and contact piece 6 together.

The insulating washer 10 is formed with a lug 13 which projects through the threaded inner shell and which is adapted to impinge against a bar 14 of a key 15 said key being adapted to be inserted through an opening 16 in the outer shell and into a cavity 17 in the block, so that when it is desired 70 to remove the lamp from the socket it can be unscrewed by turning it in one direction and causing the lug 13 to impinge against the bar 14 on the key. The key can be removed by turning it up in the cavity 17 in 75 the block and withdrawing it through the slot 16 which is arranged in transverse position in the capsule. The upper end of the threaded inner shell is formed with an upwardly projecting spring 18 which is adapted 80 to sweep over the lower surface of the block when the lamp is turned in a direction tending to unscrew it from the capsule, said spring allowing the capsule to turn freely 85 and not permitting the lamp to be removed 90 from it.

By reversing the motion of the lamp and turning it into the socket, the spring 18 is adapted to engage the shoulder 19 in the head and hold the capsule while the lamp is 95 being screwed into the socket. Thus it is not necessary to insert the key in the socket to place a lamp therein and it is only necessary to insert a key in order that the lamp may be removed. As shown the socket is 100 provided with a switch or what is commonly known as a key for turning the current on and off but it is obvious that it need not be provided with a switch in order to fulfil 105 the requirements within the scope of my invention.

The switch shown is of ordinary construction and formed with a spring 20. A contact piece 21 is mounted on the shaft 22 and is adapted to be pressed against the threaded 110 inner shell when the shaft 22 is turned by means of the thumb piece 23 into vertical

position. Current is adapted to be conducted to the usual contacts upon the lamp by leading one side of the circuit down through the parts of the switch and to the inner shell 5 and the other side through the contact piece 6 and pindle 8, the parts of each side of the circuit in the socket being obviously insulated or spaced apart.

In accordance with the patent statutes I 10 have described the principles of operation of my invention together with apparatus which I now consider to represent the best embodiment thereof but I desire to have it understood that the construction shown is 15 only illustrative and that the invention can be carried out by other means and applied to uses other than those above set forth within the scope of the following claims.

Having described my invention what I 20 claim as new and desire to protect by Letters Patent is:

1. A device of the class set forth, comprising, in combination, an outer inclosing shell, a threaded inner shell free to turn in said outer shell, an insulating block in said outer shell having an indent, a swivel joint between said block and inner shell, a key inserted in said outer shell, key engaging mechanism associated with said inner shell 25 and a spring between said block and inner shell adapted to sweep over said block and engage therewith in said indent to prevent said inner shell from turning in one direction and allowing it to reverse.

2. A device of the class set forth, comprising, in combination, an inclosing outer shell, a lamp supporting member swiveled in said outer shell, an insulating block in 30 said outer shell above said lamp supporting member, and having an indent in its lower

surface and a yielding member carried by said lamp supporting member and adapted to sweep over said insulating block when said lamp supporting member is turned in one direction and to engage said insulating 45 block in said indent when said lamp supporting member is reversed.

3. A lamp socket of the class set forth, comprising, an inclosing shell, an insulating support within said shell, and a socket shell 50 swiveled upon said support having means operable by a key to prevent the rotation of said socket shell when a lamp is being unscrewed, and a ratchet automatically preventing the rotation of said socket shell in 55 the opposite direction when said lamp is being screwed into said socket shell.

4. A lamp socket having a swiveled lamp engaging socket shell insulated therefrom and adapted to turn when a lamp is moved 60 in a disconnecting direction, and a ratchet adapted to automatically hold the lamp engaging member against rotation while a lamp is being secured in said engaging member.

5. A lamp socket having a swiveled lamp engaging socket shell insulated therefrom and adapted to turn when a lamp is moved 70 in a disconnecting direction, and means adapted to automatically hold the lamp engaging member against rotation while a lamp is being secured in said engaging member.

In testimony whereof, I have signed my name to this specification, in the presence of 75 two subscribing witnesses.

AUGUST J. KEMPIEN.
